UNITED STATES PATENT OFFICE.

CARL ELSENER, OF IBACH-SCHWYZ, SWITZERLAND.

DESIGN FOR A SAFETY-RAZOR.

59,544.

Specification for Design.

Patented Nov. 1, 1921.

Application filed February 5, 1920. Serial No. 356,408. Term of patent 3½ years.

To all whom it may concern:

Be it known that I, CARL ELSENER, residing at Ibach-Schwyz, Canton Schwyz, Switzerland, have invented a new, original, and ornamental Design for a Safety-Razor, of which the following is a specification, reference being had to the accompanying drawings, forming part thereof.

Figure 1 is a side view of the design.

Fig. 2 is a rear view of the design.

Fig. 3 is a top view of the design.

Fig. 4 is a sectional elevation of the design.

Fig. 5 shows the design in a perspective view.

I claim:

The ornamental design for a safety-razor as shown.

CARL ELSENER.
